UNITED STATES PATENT OFFICE

GÜNTHER KEMPF, OF HAMBURG, GERMANY

SHIP'S HULL

Application filed January 14, 1931, Serial No. 508,739, and in Germany August 24, 1929.

Efforts to increase the speed, controllability, and so forth, of ships extend both to the shape of the ship and to the accessories thereof, such as steering or rudder appliances and 5 also to the driving means.

The present invention relates to an improvement in the form of the ship for the purpose of shaping the current of water flowing to the rear of the ship uniformly, and there- 10 by preventing the formation of dead water eddies in front of the propeller, increasing the driving effect of the propeller and obviating disadvantages such as vibrations, air suction and the like. The idea of the inven- 15 tion is embodied in a definite construction, in which, as compared with the more or less V-shaped cross sections of the form of the after part of a ship's hull hitherto usual, sub- 20 stantially pear-shaped cross sections are pro- vided in front of the propeller. For the better understanding of the invention, the generally known form of the after part of a ship's hull will first be explained.

In the accompanying drawings, Figures 1 25 and 2 are diagrams representing the usual construction of the after part of a ship, and

Figures 3 and 4 are similar diagrams illustrating the construction of the after part of a ship according to the present invention.

30 Figure 1 is a rear end view of a ship's hull represented in the manner with which ship-builders are familiar, and showing sections on the lines 1, 2, 3, 4, 5, 6 and 7 in Figure 2. Planes of section pass through characteristic 35 positions near the stern of the ship, and are so arranged that the boundary lines are formed by the lines of intersection of the planes of section perpendicular to the keel plane with the outer skin of the ship.

40 The lines 8, 9 and 10 represent the characteristic stream lines assumed for the purpose of distinguishing the mean directions of flow along which the water flowing towards the propeller moves. The circles in Figures 1 and 45 3 represent the circles passing through the tips of the propeller blades and the centres of these circles represent the centres of the propeller shafts. The stream line 8 passes through the uppermost point of the propeller 50 circle, parallel to the plane of flotation. The

stream line 9 is likewise parallel to the axis of the propeller. Underneath the line 9, the direction of flow, as indicated by the line 10, which is inclined at an angle of 45° executes an oscillation corresponding to the curvature 55 of the lines 7, 6, 5, and so forth. From the line 9 onwards the directions of flow, and the stream lines characterizing them upon the outer skin extend unitarily to the centre point 60 of the propeller shaft.

In Figures 2 and 4, three characteristic stream lines 8, 9 and 10 are drawn, those in Figure 2 representing the stream lines of the normal form of ship hitherto known, and those in Figure 4 representing the stream lines 65 of the new form of hull constructed according to the present invention. Whereas hitherto the inclination of the stream lines in a downward direction from above was variable and became gradually more acute, the new 70 form is characterized by the feature that all the stream lines have the same inclination. In the case of double curves the inclination of the tangent at the point of inflection is the 75 inclination considered.

A second feature of the new form resides in the fact that in the case of the individual stream lines their points of maximum curvature are uniformly distributed along the 80 length of the ship, so that the points of maximum curvature of the lower stream lines lie farther back than those of the upper stream lines, as indicated in Figure 4 by the numerals 8, 9, and 10, which are placed close to the points of greatest curvature, while in 85 the case of the stream lines of normal form illustrated in Figure 2, these points of maximum curvature are irregularly located at about the same part of the ship's length.

The idea of the invention is that by the 90 uniform distribution of the curvatures in the longitudinal direction downwards from above and rearwards from the front, the formation and separation of eddies of dead water is prevented, while conversely with an equal position of all the curvatures, as indicated in Figure 2, by the numerals 8, 9, and 10, such formation and separation is promoted.

The distribution of the curvature is there- 100 fore physically of great importance as re-

gards the resistance formation, because any curvature of form produces an acceleration of the liquid flowing along it and a diminution of pressure by centrifugal action. A summation of these effects at the same place acts injuriously upon the formation and resistance and separation of eddies.

Hence the object of the invention is to hinder the formation of separation eddies or dead water eddies at the after part of the ship and to supply to the propeller, while preserving the normal form of stern, water flowing as uniformly as possible, and thus to increase its efficiency. Since the invention provides the solution of this problem while taking into consideration the existing normal stern conditions of single-screw ships, the form characterized may also be applied to existing ships by providing a supplementary structure in front of the propeller.

20 What I claim is:

1. A ship's hull, so shaped in its after part that of the stream lines arising on the outer skin of the ship from the horizontal sections through the after part of the ship at different heights, those that are uppermost have their maximum curvature farther forward than those beneath them, so that a line joining the points of maximum curvature of the various stream lines shows a displacement of these points starting from the top in the front and extending in a downward direction towards the rear.

2. A ship's hull as claimed in claim 1, the form of which is further characterized by the feature that a horizontal stream line passing through the uppermost point of the propeller circle, a horizontal stream line passing through the centre of the propeller circle, and a stream line passing through the centre point of the propeller circle at an angle of forty-five degrees, all have the same angle of slope at the centre of the propeller.

In testimony whereof I have signed my name to this specification.

GÜNTHER KEMPF.
